UNITED STATES PATENT OFFICE

HENRY A. DREFFEIN, OF CHICAGO, ILLINOIS

HEAT TREATING PROCESS

Original application filed November 28, 1930, Serial No. 498,669. Divided and this application filed July 13, 1931. Serial No. 550,529.

This invention relates to processes for heat treating metals and more particularly to a process for annealing or normalizing sheet metals, and is a division of my co-pending application, Serial No. 498,669, filed Nov. 28, 1930.

An object of this invention is to provide a process for heat treating metal sheets or the like, as, for example, to a temperature which will effect normalizing and thereafter quickly and satisfactorily cooling the same in a minimum of time in a reducing or non-oxidizing atmosphere.

Another object of the invention is to provide a process of heat treating which effects decided economies in plant structure and apparatus usually employed for the purpose.

A further object of the invention is to provide means in a heat treating process for rapidly cooling the treated material in a reducing atmosphere before it leaves the treating furnace or unit.

Still another object of the invention is to provide in a heat treating process for utilizing the products of combustion of the heating means in preventing the transfer by radiation or conduction of heat from the chamber in which the heating is accomplished to a cooling chamber contiguous thereto in such a manner that the treated material in passing from the heating to the cooling chambers encounters a temperature gradient which will assure satisfactory annealing or normalizing of such material in a relatively short time.

Other objects and advantages inherent in this invention will be more fully pointed out in the following description and accompanying drawings, in which:

Fig. 1a is a sectional plan view of a portion of a heat treating furnace adapted to the practice of the present processes looking from the charging end thereof;

Fig. 1b shows the same view looking toward the discharge end of the furnace;

Fig. 2a is a sectional elevation of the portion of the furnace shown in Fig. 1a; and

Fig. 2b is a sectional elevation of that portion of the furnace shown in Fig. 1b.

Throughout the drawings like numerals refer to similar elements.

In Figs. 1a and 1b are illustrated in horizontal section the major portion of the heating chamber 10 of a furnace suitable for the practice of my process. This chamber extends to the restricting baffle 11, part shown in Fig. 1b, at which point begins the cooling chamber, generally designated by numeral 12.

The walls and floor of the heating and cooling chambers are formed of suitable refractory material, there being slots 14 in the floor of the chambers to permit the passage of conveyor members for the continuous conveyance of metal sheets, or the like, through the furnace structure. At the entrance or charging end 8 of the furnace 5 is provided a vertically adjustable door 16 (better shown in Fig. 2a) and similarly there is provided at the discharge end of the furnace an adjustable door 17 (Fig. 2b).

I have found it expedient and desirable to use for heat generation and supply the invention disclosed in my Patent No. 1,779,759 issued October 28, 1930, although I do not wish to be restricted to the specific combustion units except as limited to details thereof by the claims. At one side of the heating chamber adjacent the charging end 8 thereof the wall is offset at 18 to accommodate a burner 19 into and through which I introduce at substantial velocity an admixture of fuel and air, such as producer gas and air. Opposed to the burner 19 and spaced therefrom is a restricted chamber 20, formed by the wall 21, there being a gap 22 between one end of said wall and the offset furnace wall 18. At the top of the wall 21 are ports or passages 23 (see Fig. 2a) formed by the partitions 23-a extending upward from the top of the wall 21. These partitions 23-a are inclined in such wise as to direct the gases flowing out of the chamber 20 into the heating chamber 10, partially toward the entrance end of the heating furnace. The restricted chamber 20 is terminated at the end opposed to the burner 19 by the wall 25, at the opposite side of which is another restricted chamber 27.

formed by a partition wall 28 having partitions 28-a extending upward from the wall 28. These partitions are substantially at right angles to the major axis of the furnace structure. In alignment with the restricted chamber 27 is the burner 30 similar to burner 19, there also being a similar gap 31 between the burner and the wall 28.

These combustion units function similarly. Burning fuel mixture is introduced, as stated, at substantial velocity through or from the burner 19 whence it flows toward and into the restricted chamber 20, for example, past the gap 22, radiant heat being transmitted there across but without substantial contact of the burning gases with the product passing through the furnace. A pressure is set up in the restricted chamber 20 and the products of combustion flow therefrom through the ports 23 adjacent the roof of the furnace structure, transversely of the same, over, around and in contact with the metal sheets, for example. The flow of gases into the restricted chamber 20 is such as to set up an inductive action whereby a portion of the products of combustion is induced into recirculation with the gases flowing into the restricted chamber. Due to the inclination of the partitions 23-a, the flow of gases from the restricted chamber 20 is such as to enhance or aid the general flow of gases in the furnace toward the charging end thereof. As stated, a similar action obtains in the opposed adjacent burner unit except that the gases flow from the restricted chamber 27 at right angles to the general flow of the gases through the heating chamber.

At the opposite sides of the furnace is provided a similar pair of burner units generally indicated by numerals 33 and 34, being staggered with respect to the first described units. The function and operation is identical with those previously described. The side walls of the furnace are offset or inset to accommodate the burners affording easy access to the air supply ducts 35 and gas supply ducts 36 for adjustment or regulation.

The supply of fuel and air is preferably such that pressure is set up in the heating chamber in excess of atmospheric to prevent infiltration of air. The arrangement of the ports from the respective restricted chambers is such as to assist or enhance the general flow of gases toward and out the charging end of the heating chamber. With the burner units of the character described and arranged as described, products of combustion will be successively picked up and recirculated in part as they pass each heating unit, so that some of the gases are repeatedly reheated and recirculated in their travel through the heating chamber, which contributes markedly to

the efficiency of operation. Also with the heat supply means described, relatively few burners are required, which makes for flexible and positive control and operation.

Also since the sheets or other product being heated, are received at the charging end at a relatively low temperature, they are met by the outflowing gases and encounter an increasing temperature as they flow toward the discharge end of the furnace since, as their temperature increases, they exercise a lesser cooling action upon the products of combustion. Another advantage resides in the fact that the gases during combustion thereof need not be contacted with the product, but only products of combustion which eliminates the hazardous stratification of air and fuel which might cause oxidization of the sheets. It also reduces the deposit of soot, tarry substances or the like upon the sheets. Forming a continuation with the heating chamber is the cooling chamber 12, there being a restricting transverse wall or baffle 11, previously described, with an opening 11-a therethrough to permit the passage of the sheets and the conveying means. Leading from the heating chamber, preferably at the charging end thereof, is the outlet 40 communicating with the extended exterior duct 41 having the initial portion 41-a thereof insulated in the embodiment illustrated. This duct 41 is located above the furnace structure and leads to an exhauster or fan 43, shown as driven by an electric motor 44 through the medium of a belt 45. From the fan 43 leads the elbow or delivery pipe 47 through the top of the cooling chamber into communication with a transversely extending box 48 having outlet orifices 48' arranged to deliver jets of gas downwardly upon and along the surfaces of the sheets just prior to their discharge from the cooling chamber 12. Extending upwardly from the roof of the cooling chamber adjacent its junction with the heating chamber is a plurality of vent pipes or stacks 49, each of which is provided with an adjustable damper 50.

Extending transversely through the cooling chamber intermediate its extremities is a plurality of air pipes 52, terminating at each end in a manifold or header 53-54, these headers being located on the outside of the cooling chamber for convenience. Communicating with the header 53 is the duct 55 also in communication with a motor driven fan 56, which supplies atmospheric air to the header 53, pipes 52 and header 54. From the last, leads a duct 57 and a branch duct 58, the former communicating with the adjacent burner to supply air thereto, and the latter to the opposed burner as illustrated in Fig. 1b. Similarly a branch 59 is provided to supply air to the burners on the opposite side of the heating chamber.

Pipes 52 are located above the plane of travel of the sheets in the cooling chamber and in the embodiment shown begin a substantial distance from the restricting wall

5 11.

A motor 60, speed reducing mechanism 61 and chain 62 together with suitable sprockets furnish driving power for the shaft 63, which carries sprockets 64 for actuation of 10 the conveyer mechanism which may be of any suitable construction.

In the practice of my process with apparatus of the type described above, metal sheets, for example, are continuously fed 15 into the heating chamber through the charging end thereof where they encounter the outflowing heated gases. They are subjected to an increasing temperature as they travel toward the discharge end of the heating chamber until the desired maximum is 20 reached, as, for example, from 1750° F. to 1950° F. for normalizing. The heated gases of combustion, as stated above, flow rearwardly from the discharge end of the heating chamber toward the charging end thereof, a portion of said gases being picked up 25 in their flow past each of the restricted chambers and induced into recirculation with the incoming burning or burned gases 30 for subsequent delivery into the heating chamber proper. From the heating chamber the sheets travel into and through the cooling chamber 12, arriving therein at a maximum temperature. During this travel 35 through the cooling chamber they are submitted to the cooling action of the products of combustion which have been extracted from the heating chamber by the exhaust 40 43 through duct 41. These cooling gases are delivered downwardly and upon and around these sheets as they are about to pass out of the cooling chamber, so that the flow of cooling gases is toward the heating chamber. During this flow of the cooling gases they 45 encounter sheets which present a generally rising temperature as these cooling gases progress against the direction of movement of the sheets and are raised in temperature to a maximum where they encounter the 50 sheets at their maximum temperature when they are passed from the heating chamber into the cooling chamber. This insures against subjecting the sheets to a marked drop in temperature as they pass from one 55 chamber to the other, while at the same time their temperature is rapidly but more or less uniformly reduced to the desired point when they leave the cooling chamber.

The heated cooling gases, as they approach 60 the barrier 11, in part at least, will then flow upwardly and back along the roof of the cooling chamber, and in part those beneath the sheets will be forced rearwardly 65 along the floor of the cooling chamber for outward flow through the discharge open-

ing of the furnace. The spacing of the orifices 48' permits this discharge of the upper rearwardly flowing hot gases.

The pipes 52 conveying air at atmospheric temperature serve materially to cool or contribute to the maintenance of the cooling gases in relatively cooled condition in their flow in the cooling chamber, thus contributing to the rapid cooling of the sheets. At the same time the heat which is extracted from the cooling gases by the air in the pipes 52 serves to preheat such air prior to its delivery to the burners, which also adds to the efficiency of operation as will be readily recognized by those skilled in the art. The long travel through the duct 41 permits the substantial radiation of heat from the extracted gases and products of combustion, so that they are very substantially reduced in temperature before they 85 are discharged into the cooling chamber. The operation of the exhauster 43 may be controlled to set up any desirable pressure in the cooling chamber, so that the pressure of the gases in the heating chamber may be 90 balanced or, if desired, overbalanced by the pressure of the cooling gases, so that the latter serve to baffle or obstruct the flow of heating gases and prevent their substantial entry into the cooling chamber. A damper 95 41-b is provided in duct 41 on suction side of exhauster 43 for control of gas flow through duct 41 and consequent cooling effect. In this wise cooling gases are or may be utilized to initiate and contribute to the rearward flow of the heating gases toward the charging end of the furnace, as described above.

An increase in the quantity of the product being handled by the furnace may require 105 an increase in the cooling action in the cooling chamber, in which event an increased delivery of cooling gases may be required. In such event, in addition to use of the damper 41-b, the dampers 50 in the vent 110 pipes or stacks 49 may be adjusted to permit the necessary discharge of cooling gases into the atmosphere, thereby permitting an increased delivery of such cooling gases 115 without increasing the amount thereof which are recirculated in the cooling chamber.

By the construction and process described above, I am enabled to use a relatively very 120 short length of cooling chamber with respect to the associated heating chamber. In fact, in a furnace of approximately overall length of one hundred feet I have been able to devote seventy feet thereof to the heating 125 chamber and thirty feet thereof to the cooling chamber, while obtaining temperatures of 1750° F. to 1950° F. in the heating chamber with a reduction of the temperature of the sheets in the cooling chamber before dis- 130

charge thereof to from 800° F. to 1200° F., i. e. to a dull red heat or therebelow.

I find it desirable in the practice of my process to thus heat the sheets to the desired temperature in the heating chamber and thereafter cool them to or below a dull red heat while maintaining a reducing or non-oxidizing atmosphere, after which they may be discharged into the open air without danger of scaling, oxidization or other impairment.

The advantage of being able to devote as much as possible of the length of a furnace of this character to the annealing, normalizing or other heating operation will be readily appreciated by those skilled in the art, particularly as the cost of such structures is more or less proportional to the length thereof. Therefore, the less such structures are utilized for cooling the greater capacity and efficiency which will be obtained.

It will be obvious that my process and apparatus are susceptible of modification and I do not wish to be restricted to the forms illustrated and described, except as I may be so restricted by the appended claims properly interpreted with respect to the prior art.

What I claim is:

1. A process of treating metal sheets consisting of passing said sheets through a heating chamber, supplying heating gases to said chamber in such wise as to maintain a non-oxidizing atmosphere, and heating said sheets to the desired temperature, thereafter continuing the travel of said sheets through a cooling chamber, and flowing products of combustion therein against the line of travel of said sheets and maintaining a non-oxidizing atmosphere in said cooling chamber.

2. A process of treating metal sheets consisting of passing said sheets through a heating chamber, supplying heating gases to said chamber in such wise as to maintain a non-oxidizing atmosphere and heating said sheets to the desired temperature, thereafter continuing the travel of said sheets through a cooling chamber, and supplying products of combustion thereto for cooling said sheets, and forcing said products of combustion back against the advancing sheets, maintaining a non-oxidizing atmosphere in said cooling chamber and reducing the temperature of said sheets to a point approximating that of a dull red heat or less.

3. A process of treating metal sheets consisting of advancing said sheets through a heating chamber, supplying heating gases to said chamber in such wise as to maintain a non-oxidizing atmosphere and heating said sheets to the desired temperature, thereafter continuing the travel of said sheets through a cooling chamber, and supplying products of combustion thereto for cooling said sheets, said products of combustion be-

ing flowed back over the advancing sheets maintaining a non-oxidizing atmosphere in said cooling chamber and cooling said sheets to approximately 1200° F. or less therein.

4. A process of treating metal sheets consisting of passing said sheets through a heating chamber, supplying heating gases to said chamber in such wise as to maintain a non-oxidizing atmosphere and heating said sheets to approximately 1750° F. or more, thereafter continuing the travel of said sheets through a cooling chamber, supplying products of combustion thereto for cooling said sheets, and causing said products of combustion to flow against the movement of said sheets, and maintaining a non-oxidizing atmosphere in said cooling chamber.

5. A process of treating metal sheets consisting of passing said sheets through a heating chamber, supplying heating gases to said chamber in such wise as to maintain a non-oxidizing atmosphere, and heating said sheets to the desired temperature, thereafter continuing the travel of said sheets through a cooling chamber, extracting products of combustion from said heating chamber, cooling and discharging the same into said cooling chamber to cool said sheets passing therethrough.

6. A process of treating metal sheets consisting of passing said sheets through a heating chamber, supplying heating gases to such chamber, flowing said gases in said heating chamber in a direction opposite to the direction of travel of said sheets, thereafter passing said sheets into and through a cooling chamber while supplying cooled products of combustion thereto.

7. A process of treating metal sheets consisting of passing said sheets through a heating chamber, supplying heating gases to such chamber, flowing said gases in said heating chamber in a direction opposite to the direction of travel of said sheets, thereafter passing said sheets into and through a cooling chamber while supplying products of combustion thereto, said products of combustion being flowed in a direction opposite to the direction of travel of said sheets.

8. A process of treating metal sheets consisting of passing said sheets through a heating chamber, supplying heating gases to said chamber, thereafter passing said sheets through an extension of said heating chamber comprising a cooling chamber, and supplying cooled products of combustion to said cooling chamber in sufficient quantity to baffle and obstruct the flow of heating gases thereto from said heating chamber.

9. A process of treating metal sheets consisting of first passing the same through a heating chamber against the flow of heating gases and thereafter into a cooling chamber

against the flow of cooled products of combustion.

10. In metal treating processes which include the steps of heating the metal by combustion in a heating chamber, and passing it through a cooling chamber, the method of maintaining a desired temperature in said cooling chamber, which comprises removing gases of combustion from said heating chamber, cooling them and flowing them uniformly over the hot metal in said cooling chamber.

11. The method of normalizing metals which comprises heating such metals in a heating and combustion chamber free from oxidizing gases, passing said heated metal through a contiguous cooling chamber, extracting products of combustion from said heating and combustion chamber, cooling the same, and flowing them back over the heated metals passing through said cooling chamber.

12. In normalizing furnaces having heating chambers provided with combustion means and a contiguous cooling chamber and means for conveying materials to be normalized continuously from said heating chamber through said cooling chamber, the method of maintaining desired temperatures in said cooling chamber, which comprises extracting quantities of products of combustion from said heating chamber, cooling the same, and flowing them uniformly and continuously through said cooling chamber in a direction opposite to the movement of materials carried by said conveying means.

13. In a normalizing process including the steps of heating a metal in a combustion chamber and passing it through a length of cooling chamber, the method of cooling which comprises extracting products of combustion from said combustion chamber, cooling the same, and forcing them in a counter flow from the remote extremity of said cooling chamber back toward said combustion chamber, and baffling the infiltration of heat from said combustion chamber to said cooling chamber by said counter flow.

14. In witness whereof, I hereunto subscribe, my name this 6 day of July, 1931.

HENRY A. DREFFEIN.
